UNITED STATES PATENT OFFICE

145,642

DESIGN FOR A COMBINED WASHING MACHINE AND WRINGER OR SIMILAR ARTICLE

John H. Walter, Detroit, Mich., assignor to Nineteen Hundred Corporation, St. Joseph, Mich., a corporation of New York

Application September 19, 1945, Serial No. 122,171

Term of patent 7 years

(Cl. D49—1)

To all whom it may concern:

Be it known that I, John H. Walter, a citizen of the United States and a resident of the city of St. Joseph, in the county of Berrien and State of Michigan, have invented a new, original, and ornamental Design for a Combined Washing Machine and Wringer or Similar Article, of which the following is the specification, reference being had to the accompanying drawing, forming a part thereof.

On the drawing:

Figure 1 is a front view, slightly in perspective of a combined washing machine and wringer or similar article, showing my new design;

Figure 2 is a similar view thereof taken from the right of Figure 1; and

Figure 3 is a similar view of the rear thereof.

I claim:

The ornamental design for a combined washing machine and wringer or similar article, as shown.

JOHN H. WALTER.
